FOLDING UMBRELLA.
APPLICATION FILED APR. 17, 1917.

Patented Apr. 2, 1918.

Fig. I.

Fig. 3

Fig. 4.

A technical drawing of a mechanical assembly. It features a central vertical plate with a slot. A horizontal bar, labeled 23, is positioned above the slot. A vertical rod, labeled 21, is attached to the side of the central plate. A small circular component, labeled 29, is attached to the top of the vertical rod. The entire assembly is labeled 'Fig. 5.' in cursive script.

UNITED STATES PATENT OFFICE.

FLOYD E. DIXON, OF ROME, PENNSYLVANIA.

FOLDING UMBRELLA.

1,261,722.

Specification of Letters Patent. Patented Apr. 2, 1918.

Application filed April 17, 1917. Serial No. 162,671.

To all whom it may concern:

Be it known that I, FLOYD E. DIXON, a citizen of the United States, residing at Rome, in the county of Bradford and State 5 of Pennsylvania, have invented new and useful Improvements in Folding Umbrellas, of which the following is a specification.

This invention relates to umbrellas and more particularly to umbrellas of the folding 10 type.

The primary object of the invention is to provide an umbrella which may be quickly and compactly folded in such manner as to permit it to be carried in an ordinary trav- 15 eling bag.

Another object is to provide a folding umbrella with novel means connecting the rib sections together in order to space them apart when the umbrella is folded, to pro- 20 vide a space therebetween to receive the folded cover in a manner to prevent cutting or wearing the same by contact with the ad- jacent folded rib sections.

A further object is to provide a novel 25 form of pivot between the rib sections and the braces therefor, to hold the said sections in alined position when the umbrella is open and to prevent contact of the pivot means with the cover of the umbrella.

The invention further contemplates a 30 novel means for holding the handle sections extended, said means consisting of spring actuated catches to provide means whereby, when it is desired to close the umbrella, one 35 of said catches will be automatically re- tracted to facilitate this operation.

With the above and other objects in view, the invention consists of the following novel 40 combination and arrangement of parts hereinafter more fully described and illustrated in the accompanying drawings, in which

Figure 1 is a central section view through 45 a portion of an umbrella constructed in accordance with the present invention, showing the same extended;

Fig. 2 is a similar section with the um- 50 brella folded;

Fig. 3 is an enlarged sectional view show- 55 ing the manner of pivotally connecting the rib sections with the braces;

Fig. 4 is a similar view of this connection showing the same folded and illustrating the manner of spacing the rib sections apart to provide for the folding of the umbrella 55 cover therebetween; and

Fig. 5 is a transverse sectional view upon the line 5—5 of Fig. 4.

Referring to the drawings in detail, the reference character 10 designates the handle of the umbrella, which comprises the sec- 60 tions 11, 12 and 13, the latter section forming that portion of the handle which is used for holding the umbrella when in its extended position. This section 13 is of 65 tubular form, being preferably formed with a closed end or knob 14 to afford a convenient means of grasping the same. It is of course understood that any other form of handle or grip may be employed for the one shown. The section 13 is open at its oppo- 70 site end to provide for the reception of the section 12, which telescopes therein, this section 12 carrying a spring actuated catch 15, which is provided with an engaging head 16, adapted to contact with the upper edge 75 of the section 13 to hold the two sections in an extended position. The section 12 is also of tubular form and is adapted to receive the section 11, which carries a spring actuated catch 17, which is adapted to engage a 80 slot or opening 18 in the section 12, when the handle is extended. The catch 17 is of novel formation, being inclined inwardly toward its lower end to provide a beveled face 19, for engagement with the upper end of the 85 section 13, when the handle is being closed. This engagement will cause the catch 17 to be automatically retracted within the section 11, so as to permit the three sections 90 mentioned to be telescoped one within the other, without manually operating this catch.

Secured to the outer end of section 11 is a substantially crown shaped element 20, to which are pivotally connected the inner ends 95 of the rib sections 21 and by means of which they are pivoted at a slight distance from the section 11 to provide for the reception of the sections 12 and 13 therebetween when the umbrella is folded. These rib sections 100 21 are provided with rounded edges 22 for contact with the cover 23 of the umbrella, in order to prevent these sections from cutting or wearing of said cover. The outer ends of sections 21 are slotted as shown at 24, and 105 within these slotted ends are pivoted the outer ends of braces 25, the pivots of these braces being shown at 26. The opposite ends of the braces 25 are pivoted to the upper ends of the section 12 as shown at 27.

The ends of the braces 25 which are pivoted within the slots 24 are formed or provided with angular extensions 28, which when the umbrella is open are adapted to lie wholly within the slots 24, so as to be out of contact with the cover 23. Pivots secured to the extremities of these extensions are outer rib sections 29, the inner ends of which also lie wholly within the slotted ends 24 of the sections 21 when the umbrella is open. These sections 29 are also provided with a rounded surface 30 for engagement with the umbrella cover, which cover is secured to the outer ends of these sections in a well known or any approved manner.

By connecting the sections 29 to the braces 25 in the manner shown, there is provided a space 31 between the rib sections 21 and the sections 29, when the umbrella is folded, which provides room for the folding of the umbrella cover between the adjacent folded rib sections, in a manner to prevent the squeezing or binding of this cover between the sections for the purpose of preventing the cutting or wearing of the cover as would otherwise occur.

In order to aid in the opening of the umbrella, the usual extending end of the handle 30 or rod is dispensed with, and in its place there is provided a ring 32, which is secured within the handle section 11, preferably by means of a threaded shank 33 engaging the threaded socket formed in the end of this section.

When the umbrella is folded in the position shown in Fig. 2 of the drawings, the handle is grasped in one hand and the ring 32 in the other and the sections are pulled apart. This action separates the telescopic sections of the handle, the section 12 carrying with it the braces 25, which opens the umbrella cover, the handle sections being pulled apart until the catches 16 and 17 spring into their respective slots. When it is desired to fold the umbrella, it is only necessary to manually disengage the catch 16 from the section 12 and push the sections together, the engagement of the sections 13 with the catch 17 retracting this catch and passing over the same until it contacts with the end of the section 12 to which the braces 25 are pivoted, carrying upward both of the said sections 12 and 13 and seating their upper ends within the space provided between the section 11 and the pivots 20 of the ribs.

The outer rib sections may then be folded inwardly against the sections 21, leaving a space 30 between the folded rib sections in a manner previously described. 60

Various changes in the form and proportion of the invention may be made as will fall within the scope of the appended claims, and the right is reserved to make such changes. 65

Having described the invention, what is claimed is:

1. A folding umbrella embodying a collapsible stick, sectional ribs, braces pivotally connected to the sectional ribs and to said stick, angular extensions formed on the end of the braces at the point of connection with the sectional ribs and means for holding the stick in an extended position. 70

2. A folding umbrella embodying a collapsible stick, sectional folding ribs pivotally connected to said stick, one section of said ribs being formed with slotted ends, braces pivotally secured within said slotted ends and to said stick, angular extensions 80 formed on said braces and adapted to lie within the slotted ends of the rib sections, other rib sections pivoted to said angular extension to form complete ribs and means for holding the stick in an extended position. 85

3. A folding umbrella embodying a collapsible stick, inner rib sections pivoted at one end of said stick, braces pivoted to the opposite ends of said rib sections and to said stick, angular extensions formed on said braces, outer rib sections pivoted to said angular extensions in a manner to space the inner and outer rib sections apart when the umbrella is folded and means for holding 95 the stick in extended position.

4. A folding umbrella embodying a collapsible stick, ribs formed of inner and outer sections pivotally connected to said stick, braces having one end pivotally connected to said stick and the other end pivotally connected to the inner end of the outer section of the ribs and an extension formed on said braces, said extension being pivotally connected at its outer end to the outer end of 100 the inner rib section in a manner to form a continuous rib when the umbrella is open and to space said rib sections apart when the ribs are folded. 105

In testimony whereof I affix my signature. 110

FLOYD E. DIXON.
